(57) CLAIM

The ornamental design for a data input and output device, as shown and described.

DESCRIPTION

FIG. 1 is a perspective view of the front, bottom and right side of a data input and output device showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom view thereof.

The elements shown in phantom lines do not form any part of the claimed design.

1 Claim, 5 Drawing Sheets
